INSULATED FOOD CARRIER

Thordis Grace Hallbeck, 328 W. Ethel Ave.,
Lombard, Ill. 60148

Filed Nov. 2, 1967, Ser. No. 9,261

Term of patent 7 years

(Cl. D44—1)

FIG. 1.

FIG. 2

FIG. 4

FIG. 3

FIG. 1 is a perspective view of an insulated food carrier showing my new design;

FIG. 2 is a sectional view on line 2—2 of FIG. 1;

FIG. 3 is a sectional view on line 3—3 of FIG. 1; and

FIG. 4 is an enlarged scale fragmentary sectional view taken substantially on line 4—4 of FIG. 1.

The eating utensils and food portions shown in broken lines in FIGS. 2 and 3 are for illustrative purposes only.

I claim:

The ornamental design for an insulated food carrier, substantially as shown and described.
